Primary Examiner — Antoine D Davis(74) *Attorney, Agent, or Firm* — Banner & Witcoff, Ltd.(57) **CLAIM**

The ornamental design for a display screen with user interface, as shown and described.

DESCRIPTION

The FIGURE is a front view of a display screen with user interface showing our new design in the environment of a handset.

The broken lines of the display screen with user interface in showing environment and the unshaded regions therein are for illustrative purposes only and form no part of the claimed design.
